MANUFACTURE OF PROPELLER BLADES

David J. McComb, Emsworth, Pa., assignor to
Curtiss-Wright Corporation, a corporation of
Delaware

Application January 29, 1944, Serial No. 520,361

3 Claims. (Cl. 29—156.8)

1

My invention relates to improvements in the art of manufacturing propeller blades.

My invention further relates to a method of locating one or more blade surfaces in predetermined position relative to a reference line or surface.

My invention further relates to a method of locating the center of gravity of a propeller blade in predetermined position relative to said reference line or surface.

My invention also relates to machining the rough-turned shank of the propeller blade, thereby producing a new shank surface in desired position relative to said reference line or surface, this machining being done after said first-named blade surfaces or said center of gravity, or both have been located in predetermined position relative to said reference line.

A more specific form of my invention involves the use of a tubular sleeve adapted to receive and retain the rough-turned propeller shank therein. Means are provided for adjusting the position of said propeller blade relative to the extended longitudinal axis of said sleeve which acts as the reference line referred to before.

In the description, reference will be had to the accompanying drawings, in which:

Figure 1 is a perspective view of a reading table illustrating its use in my blade balancing method;

Fig. 2 is a sectional view, partially in elevation, illustrative of one use of the reading table;

Fig. 3 is a sectional view, partially in elevation, illustrative of another use of the reading table;

Figs. 4 and 5 are schematic views showing features of the invention;

Fig. 6 is a perspective view showing a blade balancing apparatus as used in my invention;

Fig. 7 is a side elevational view, partially in section, illustrating another use of the balance stand in accordance with the invention;

Figs. 8 and 9 are schematic views illustrating features of the invention;

Fig. 10 is a reduced side view showing the application of my invention to a modified form of propeller blade; and

Figs. 11 and 12 are diagrammatic views illustrating the use of a lathe in accordance with my invention.

The novel blade balancing method of my invention is practiced by using certain apparatus commonly employed in the art of manufacturing airplane propeller blades. This apparatus will be described before disclosing my novel blade balancing method.

Referring to Fig. 1, I have shown a reading

2

table comprising the rectangular metal base 1 having a longitudinally-extending central groove 1a. A plurality of suitably spaced index lines 1b extend transversely of the base 1, these lines designating different stations as known in the propeller blade manufacturing art.

Secured to the base 1 by suitable clamps 2a is the head 2 comprising the lower section 2b and a complementary upper section 2c hinged thereto. The upper section 2c may be held in engagement with the lower section 2b by the clamps 2d. In such engaged position, said upper section 2c and said lower section 2b mutually define a central cylindrical passage 2e extending longitudinally of the base 1.

The base 1 further carries a measuring device 3 slidably supported upon the base 1 by the blocks 3a and the plate 3b, which comprises a tongue, not shown, disposed within the aforesaid groove 1a together with a transverse surface 3c which indicates the position of the measuring device 3 with respect to the aforesaid index lines 1b. Integral with said sliding blocks 3a and said plate 3b is the transverse member 3d comprising a transverse groove 3e in which the triangular templates 3f, 3f may slide, the respective inner surfaces 3g of said templates 3f being perpendicular to said transverse groove 3e. The transverse member 3d carries a scale 3h, reading outwardly in both directions from the center, said scale 3h being adapted to measure the distance of the respective inner surfaces 3g of the templates 3f from its mid-point or zero-point 0 which is included in the vertical plane VP determined by the extended longitudinal axis of the passage 2e.

Referring to Fig. 6, I have shown a blade-balancing apparatus consisting of suitable blocks 4 supporting the balance stands 4a, respectively, which, in turn, support the respective ways 4b, the respective upper surfaces 4d of which are at the same level and spaced in parallel relation.

A tubular balance hub 5 comprises the centrally located, transverse, diametrical pin 5a, the extremities of which are adapted to rest, in rolling contact, upon the upper surfaces 4d of the ways 4b. The balance hub 5 further comprises threaded diametrically extending pins 5b perpendicular to the pin 5a and adapted to receive the threaded weights 5c. In addition, the balance hub 5 comprises diametrically related slots 5d extending downwardly from the top thereof, a clamp ring 5e being circumferentially disposed about said balance hub at its upper end. A rod 6 is suitably secured to the lower end of the balance hub 5 and extends downwardly therefrom.

The lower end of the rod 6 carries the threaded weights 6a which are adjustable vertically with respect thereto.

The blade balancing apparatus is carefully constructed in order that its center of gravity will be on the longitudinal axis of the balance hub 5.

Referring to Figs. 11 and 12, I have shown a part of the stationary structure 1 of a lathe in which is journaled a cradle 8 which may be rotated by any suitable source of power, not shown, said cradle 8 comprising the tubular head 8a integral with the spaced longitudinally extending plates 8b.

The tubular head 8a carries two pairs of set screws 8c and 8d, the screws of each pair being transversely aligned in facing relation and the two pairs of screws being disposed at right angles with respect to each other. One of the plates 8b carries a clamp 8e which is movable vertically with respect to its guide member 8f, said vertical motion being controlled by the set screw 8g.

My invention also involves the use of a sleeve 10, Figs. 1, 2 and 3, of novel construction and function which comprises a tubular shank 11 corresponding diametrically with and adapted to be snugly received in the cylindrical passage 2e of the reading head 2, said tubular shank 11 having the circumferential slots 11a, which are machined to accurate circular configuration, disposed near the respective ends thereof. Integrally formed and in axial alignment with said tubular shank 11 is a tubular head 12.

The tubular head 12 carries two pairs of set screws 13a, 13b, and two other pairs of set screws 13c, 13d, the screws of each pair being transversely aligned in facing relation. The two pairs of set screws 13a, 13b are offset with respect to each other by an angle of ninety degrees and they are spaced equal distances from the inner end of the tubular head 12. Similarly, the two pairs of set screws 13c, 13d are offset with respect to each other by an angle of ninety degrees and they are spaced equal distances from the outer end of said tubular head 12. The just-described apparatus is utilized, as disclosed below, for the practice of my novel propeller blade balancing method.

Referring now to Fig. 1, the first step is to place the tubular shank 11 of the sleeve 10 upon the open lower section 2b of the head 2. The upper section 2c is then swung into facing position with respect to the lower section 2b and the clamps 2d are tightened to cause said upper surface 2c to engage said lower surface 2b, thereby firmly securing said tubular shank 11 in seated position within the head 2.

In such seated position, the extended longitudinal axis S of the sleeve 10 is parallel to the base 1 and the vertical plane VP determined by said extended axis S intersects the scale 3h at its zero-point 0 for any position of the measuring device 3 longitudinally of the base 1.

Accordingly, for any such position of the measuring device 3, the distance of the respective inner surfaces 3g of the templates 3f from the extended axis S of the sleeve 10 may be read upon the scale 3h.

As shown and preferably, the sleeve 10 is first seated within the head 2 in such position that the set screws 13a, 13c lie in a vertical plane and the set screws 13b, 13d lie in a horizontal plane which position will be hereinafter referred to as position X. For a purpose described later, the sleeve 10 may be rotated 90 degrees with respect to the head 2 to a position Y, in which the set

screws 13a, 13c lie in a horizontal plane and the set screws 13b, 13d lie in a vertical plane.

In the second step of my blade-balancing method, the sleeve 10 being in position X, the sets of set screws 13a, 13b, 13c, 13d are retracted and the shank 9a of a propeller blade 9 is placed within the tubular head 12 of the sleeve 10, in such position that the edge 3g of one of the templates 3f engages the approximately flat thrust plate A of the blade 9 substantially throughout its length at a suitable station, preferably the 42" station. Thus, the thrust plate A is perpendicular to the base 1 at the 42" station. The set screws 13c, 13d are then tightened into engagement with the blade shank 9a, thereby preventing rotation of the blade 9 with respect to the sleeve 10 with the result that the thrust plate A will be perpendicular to the base 1 at the 42" station whenever the sleeve 10 is in the described position X with respect to the head 2. Those skilled in the art will understand that the thrust plate A will form an angle with the perpendicular at the other stations, this angle increasing in a progressive manner with the distance from the 42" station.

The third step in my blade-balancing method is to center a circular blade section 9b, adjacent the shank 9a, with respect to the extended axis of the sleeve 10. As shown by Fig. 4, at this stage, the center C of said circular section 9b is usually offset both horizontally and vertically from the extended sleeve axis S.

This centering step is done as follows: The blade sleeve unit being in position X, the measuring device 3 is moved to a position near the shank 11 of the blade and the templates 3f are placed in contact with the circular section 9b engaging it at the surfaces a, a, respectively, Fig. 4, the line a1 joining said surfaces a, a, being the horizontal diameter of the circular section 9b and the center of the line a1 being the center C of the circular section 9b. For each of the surfaces a, a there is a corresponding reading on the scale 3h, the midpoint 0 of which, as previously described, is included in the vertical plane VP determined by the extended sleeve axis S. These readings, therefore, show the respective distances of the surfaces a, a from said vertical plane VP.

If said surfaces a, a are equidistant from said vertical plane VP, the horizontal diameter a1 of the circular section 9b is centrally intersected by said vertical plane VP. The center C of the circular section 9b accordingly lies on the vertical plane VP determined by the extended axis S of the sleeve 10.

Usually, however, these surfaces a, a are not equidistant from said vertical plane VP. Therefore, by tightening one of the set screws 13d, Figs. 1 and 3, and loosening the other set screw 13d, the blade, including the circular section 9b, is moved horizontally with respect to the vertical plane VP determined by the extended sleeve axis S, the surfaces a, a moving horizontally with respect to the scale 3h, for example, in the direction of the arrow, Fig. 4. This operation, involving use of the templates 3f and adjustment of the set screws 13d, 13d is repeated several times, if necessary. Finally, the respective distances of the surfaces a, a from the vertical plane VP determined by the extended sleeve axis S are equalized and the center C of the circular section 9b lies upon said vertical plane VP. Thus, the circular section 9b is centralized with respect to the vertical plane VP determined by the extended sleeve axis S. It will be understood that, at this stage, the center C of the circular section 9b is

usually vertically offset from the extended sleeve axis **S**, for example by the distance **V'**, Fig. 4.

To center the circular section **9b** with respect to the extended sleeve axis **S**, it is now necessary to move said circular section **9b** vertically relative to said extended sleeve axis **S** until the center **C** of the circular section **9b** coincides with the extended sleeve axis **S**. To this end, the blade-sleeve unit is rotated 90 degrees with respect to the head **2** to position **Y**, the circular section **9b** moving eccentrically relative to the extended sleeve axis **S** and the center **C** of the circular section **9b** moving from a vertically offset position to a horizontally offset position with respect to said extended sleeve axis **S**, as shown in Fig. 5.

The templates **3f** are again placed in contact with the circular section **9b** engaging it at the surfaces **b**, **b** respectively, Fig. 5, the line **b1** joining said surfaces **b**, **b** being the new horizontal diameter of the circular section **9b** and the midpoint of the line **b1** being the center **C** of the circular section **9b**. Since the extended sleeve axis **S** is now horizontally offset from the center **C** of the circular section **9b**, it is also included on the horizontal diameter **b1**. For each surface **b**, **b** there is a corresponding reading on the scale **3h**, the midpoint **0** of which corresponds to the intersection of the extended sleeve axis **S** and the horizontal diameter **b1** of the circular section **9b**. These readings, therefore, show the respective distances of the surfaces **b**, **b** from the extended sleeve axis **S**.

If these distances are equal, the surfaces **b**, **b** are equidistant from the sleeve axis **S** which will then be at the center **C** of the horizontal diameter **b1**. The center **C** of the circular section **9b** accordingly coincides with the extended axis **S** of the sleeve **10**.

Usually, however, these distances are unequal. Therefore, by tightening one of the set screws **13c**, Figs. 1 and 2, and loosening the other set screw **13c**, the blade, including the circular section **9b** is moved horizontally with respect to the extended sleeve axis **S**, the surfaces **b**, **b** moving horizontally with respect to the scale **3h**, for example, in the direction shown by the arrow, Fig. 5. This operation, involving use of the templates **3f** and adjustment of the set screws **13c**, **13c** is repeated several times, if necessary. Finally, the respective distances of the surfaces **b**, **b** from the extended sleeve axis **S** are equalized and the center **C** of the circular section **9b** is coincident with the extended sleeve axis **S**. This centralizes the circular section **9b** with respect to the extended sleeve axis **S**.

The set screws **13a**, **13a** and **13b**, **13b** are then tightened into engagement with the blade shank, this tightening having no effect on the set screws **13c**, **13c** and **13d**, **13d** and the centered position of the circular section **9b** maintained thereby.

Referring to Fig. 3, the fourth step is to place the surface of the thrust plate **A** at a suitable station, for example, the 42" station, a known specified distance **c** from the extended axis **S** of the sleeve **10**. This known specified distance **c** is established by the blade specifications or measurements made on a master blade.

To this end, the blade-sleeve unit is returned to position **X** and the measuring device **3** is returned to the 42" station. As previously described, the thrust plate **A** is perpendicular to the base **1** at this station, since, as stated, the blade-sleeve unit is in position **X** with respect to the head **2**. The adjacent template **3f** is placed in contact with the thrust plate **A**, the

scale **3h** showing the distance between said thrust plate **A** and the extended axis **S** of the sleeve **10**. This distance should be a known definite distance **c**, as described before. Usually, however, it is not. Therefore, by tightening one of the set screws **13b** and loosening the other set screw **13b**, the blade **9** is pivoted about the set screws **13c**, **13c** and **13d**, **13d**, the thrust plate **A** at the 42" station moving horizontally with respect to the extended sleeve axis **S**. This adjustment does not change the position of the shank surface engaged by said set screws **13c**, **13c** and **13d**, **13d** and has substantially no effect on the centered position of the circular section **9b** with respect to the extended sleeve axis **S**.

This adjustment involving the use of one of the templates **3f** and adjustment of the set screws **13b**, **13b** is repeated several times, if necessary. Finally, the thrust plate **A** is disposed at a known, specified distance **c** from the extended sleeve axis **S** at the 42" station.

If the thrust plate **A** were of perfect contour, as is the thrust plate of a master blade, the centralization of the circular section **9b**, previously described, together with the placing of the thrust plate **A** at specified distance from the extended sleeve axis **S** at the 42" station would fix the thrust plate **A** in desired, specified position relative to the extended sleeve axis **S** and said thrust plate **A** would be at specified distance from the extended sleeve axis **S** at each station along the blade surface. Usually, however, this is not so, due to imperfections in forming and shaping the blade.

The fifth step, therefore, is to determine the distance between the thrust plate **A** and the extended sleeve axis **S** at each station. To this end, the measuring device **3** is moved to another station. The blade-sleeve unit is then rotated with respect to the head **2**, until the surface of the thrust plate **A** will engage the facing edge **3g** of one of the templates **3f**. The distance, for example, **c1** of said thrust plate **A** from the extended sleeve axis **S** is then read upon the scale **3h**.

In similar fashion, readings are taken at the other stations **1b** along the base **1**, these readings showing the distance of the flat surface of the thrust plate **A** from the extended axis **S** of the sleeve **10** at each station.

The distances shown by these readings should agree with the blade specifications at each station within a prescribed tolerance limit, which is defined as the amount by which the distance of the thrust plate **A** from the extended sleeve axis **S** may vary from the specified distance at each station without causing rejection of the blade. Such a tolerance limit usually exists for each station, including the 42" station.

If at one or more stations, the distance, for example, **c1**, between the thrust plate **A** and the extended sleeve axis **S** differs from the specified distance by an amount exceeding the tolerance limit, it is necessary to move said thrust plate **A** relative to said extended sleeve axis **S** until the distance therebetween is within tolerance at said last named stations.

Therefore, in the sixth step, by tightening one of the set screws **13b** and loosening the other set screw **13b**, the blade is pivoted about the set screws **13c**, **13c** and **13d**, **13d**, the thrust plate **A** moving horizontally with respect to the extended sleeve axis **S** at each station.

As previously described, the thrust plate **A** at the 42" station was set at specified distance from

the extended sleeve axis S. In connection with the last-described movement of the thrust plate A relative to the extended sleeve axis S, the position of the thrust plate A relative to the extended sleeve axis S at the 42" station must be confined within the tolerance limits at said 42" station.

If, by this adjustment, the distances c, c1, etc., between the thrust plate A and the extended sleeve axis S is within tolerance at the respective stations, the blade is passed on to the next step. If the distance cannot thus be brought within tolerance, it is necessary to rework the blade, by hammer or press, and then repeat the fifth and sixth steps. The reworked thrust plate A is thus brought into desired alignment with respect to the extended sleeve axis S.

The sixth step of my invention is not to be limited to adjustment of the set screws 13b, 13b. If the circular section 9b is permitted to be slightly off-center with respect to the sleeve axis by the blade specifications, horizontal motion of the thrust plate A with respect to the extended sleeve axis may be obtained by adjustment of the set screws 13d, 13d.

In order to properly align the leading edge B of the blade with respect to the extended sleeve axis S, the blade-sleeve unit is rotated to position Y, Fig. 2, with respect to the head 2, with the result that the thrust plate A at the 42" station becomes perpendicular to the facing edge 3g of the adjacent template 3f, in which position said facing edge 3g contacts the leading edge B of the blade. The distance between said leading edge B and the extended sleeve axis S is read upon the scale 3h. This should be a known specified distance d, but usually it is not. Therefore, by tightening one of the set screws 13a and loosening the other set screw 13a, the blade is pivoted about the set screws 13c, 13c and 13d, 13d, the leading edge B of the blade moving horizontally with respect to the extended sleeve axis S. This adjustment is repeated several times, if necessary. Finally, the leading edge B is a known specified distance d from the extended sleeve axis S at the 42" station.

If the leading edge B were of perfect contour, as is the leading edge of a master blade, the setting of the leading edge B a known specified distance d from the extended sleeve axis together with the centralization of the circular section 9b would fix the leading edge B in desired specified relation to the extended sleeve axis S and the leading edge B would be separated the specified distance from the extended sleeve axis S at each station. Usually, however, this is not true due to imperfections in forming and shaping the blade.

Accordingly, the distance between the leading edge B and the extended sleeve axis S is measured at each station.

To this end, the measuring device 3 is moved upon the base 10 to another station. The blade-sleeve unit is rotated with respect to the reading head 2 until the surface of the thrust plate A is perpendicular to the facing edge 3g of one of the templates 3f. This is done by rotating said blade-sleeve unit, with the facing edge 3g in contact with said leading edge B until the maximum reading is obtained upon the scale 3h, this reading showing the distance d1, for example, between said leading edge B and the extended sleeve axis S.

In like manner, readings are taken at the other stations, these readings showing the distance between the leading edge B and the extended axis S of the sleeve 10 at each station.

Those skilled in the art will recognize that these distances should equal the specified distances at each station, respectively, within prescribed tolerance limits. In a manner analogous to the sixth step of aligning the thrust plate A, adjustments are made to the set screws 13a, 13a and the leading edge B is moved horizontally relative to the extended sleeve axis S. It will be understood that with some blades, this horizontal motion could be obtained by adjustments to the set screws 13c, 13c.

If, by these adjustments, the distance between the leading edge B and the extended sleeve axis S is brought within tolerance at all stations, d, d, etc., the leading edge B is then properly aligned with respect to the extended sleeve axis S.

The blade-sleeve unit is then returned to position X, Fig. 3, and the distances c, c1, etc., between the thrust plate A and the extended sleeve axis S are rechecked.

If these distances are not within tolerance, the blade is reworked, as by hammering, and the above outlined adjustments relating to the thrust plate A and the leading edge B are repeated.

If these distances are within tolerance, both the thrust plate A and the leading edge B are in correct alignment relative to the extended sleeve axis S. The blade is then ready for the next operation which involves use of the balance stand.

An object of my invention is to secure standard blade characteristics by locating the center of gravity of the blade in predetermined position. Usually, for a purpose described later, it is desired to locate the center of gravity upon the extended axis of the sleeve 10. By reason of the operations previously described, the blade is usually so disposed, relative to the extended sleeve axis, that the center of gravity either coincides with or is quite close to said extended sleeve axis.

It is necessary, then, to ascertain whether the center of gravity of the blade coincides with the extended sleeve axis. If not, minor adjustments are made to the set screws 13a, 13a, etc., moving the blade relative to the extended sleeve axis until the center of gravity of the blade does coincide with the extended sleeve axis.

To this end, the blade-sleeve unit is removed from the head 2, and mounted within the balance hub 5, the shank 11 of the sleeve 10 being secured in seated position therein by tightening the clamp ring 5e.

The tubular balance hub 5 is so constructed that its longitudinal axis coincides with the longitudinal axis of the shaft 6 and the threaded weights 6a. Moreover, when the sleeve 10 is in described mounted position within the tubular head 5, the extended axis of the sleeve 10 coincides with the longitudinal axis of the balance hub 5.

The hub 5, shaft 6, weights 6a, sleeve 10 and blade 9 are rotatable as a unit, hereinafter referred to as the balance assembly, upon the ways 4b. The extended axis of the sleeve 10 which, in view of the foregoing description, coincides with the axis of the balance hub 5, shaft 6 and weights 6a is defined as the longitudinal axis of the balance assembly.

As previously described the centers of gravity of the sleeve 10, hub 5, shaft 6 and weights 6a are upon their respective axes and, therefore, upon the extended axis of the sleeve 10. Thus, without considering the blade 9, the center of gravity of the balance assembly is upon the extended axis of the sleeve 10. If the center of

gravity of the blade 9 is offset from the extended axis of the sleeve 10, the center of gravity of the balance assembly will be offset, in corresponding direction, from the extended axis of the sleeve 10.

The balance assembly is rotated to a horizontal position, Fig. 7, and the threaded weights 6a are adjusted until said balance assembly will remain at rest in a horizontal position. In such position, the pivot of the balance assembly is the axis of the pin 5a and the center of gravity of the balance assembly is included in the vertical plane P, Fig. 7, determined by said axis of the pin 5a.

The balance assembly is then placed in a vertical position, Fig. 6, the plane P moving from a vertical to a horizontal position.

Referring now to Fig. 8, I have shown the plane P in the last-described horizontal position. Usually, by reason of the alinement steps previously described, the center of gravity CG of the balance assembly coincides with the extended sleeve axis S or substantially so. If not, it is evident that a torque is exerted upon the balance assembly, this torque being expressible as the product of the mass of the balance assembly and the radial distance R between the center of gravity CG and the extended sleeve axis S. This torque will tend to rotate the balance assembly in a vertical plane determined by said radial distance R. Alternatively, this torque could be expressed as two components, a parallel component T tending to rotate the balance assembly in a plane parallel to the ways 4b and a perpendicular component U tending to rotate the balance assembly in a plane perpendicular to the ways 4b.

The balance assembly will not rotate in response to the perpendicular torque component U due to the relation of the diametrical pin 5a to the ways 4b, Fig. 6. However, the parallel torque component T, if present, causes rotation of the balance assembly. By tightening one of the set screws 13b, Fig. 6, and loosening the other set screw 13b, the blade is pivoted about the set screws 13c, 13c, and 13d, 13d, the blade moving, in the example shown, in the direction of the arrow W, Fig. 8, with resultant motion of the center of gravity CG in the direction of the arrow W. This adjustment is repeated several times, if necessary. Finally, a position of the blade relative to the extended sleeve axis S is found in which there will be no rotation of the balance assembly. In such position, the parallel torque component T is eliminated and the center of gravity CG is laterally offset from the extended sleeve axis S, for example, at V.

The blade-sleeve unit is now rotated through an angle of 90 degrees relative to the hub 5 with resultant motion of the center of gravity CG of the balance assembly from said laterally offset position V, Figs. 8 and 9, to a transversely offset position CG, Fig. 9, relative to the extended sleeve axis S. The perpendicular torque component U, if present, is now effective in a direction parallel to the ways 4b and causes rotation of the balance assembly.

By tightening one of the set screws 13a, Fig. 6, and loosening the other set screw 13a, the blade is pivoted about the set screws 13c, 13c and 13d, 13d, the blade moving, in the example shown, in the direction of the arrow Z, Fig. 9, with resultant motion of the center of gravity CG in the direction of the arrow Z. This adjustment is repeated several times, if necessary. Finally, a position of the blade relative to the extended sleeve axis S is found in which there will be no rotation of the balance assembly. In such position, the torque

component U is eliminated and the center of gravity CG coincides with the extended sleeve axis S.

The blade sleeve unit is then removed from the balance hub 5 and replaced in the head 2, whereupon, the respective distances of the thrust plate A, Fig. 3, and leading edge B, Fig. 2, from the extended axis S of the sleeve 10 are rechecked at each station. If any of these distances differ from the specified distance by an amount exceeding the allowable tolerance, the blade is reworked and the above procedure is repeated.

If the above distances are all within tolerance, it is clear that (1) reference surfaces have been established at specified distances, within tolerance, from the extended sleeve axis S upon the thrust plate A and leading edge B of the blade 9 respectively, and (2) the center of gravity of the blade coincides with the extended sleeve axis S.

In order to complete my blade balancing method, material is cut from the shank 9a of the blade, as by a lathe, and a new permanent shank surface 9c is formed, the axis of this permanent shank 9c coinciding with the extended axis of the sleeve 10.

Accordingly, the blade-sleeve unit is removed from the head 2 and placed within the cradle 8 of the lathe, Fig. 11. The tip of the blade is engaged by the clamp 8e and may be moved vertically relative to the support 8f, this motion being controllable by the set screw 8g. Blade surfaces near the shank are engaged by the set screws 8c, 8c and 8d, 8d, adjustment of these sets of screws moving the blade vertically and horizontally, respectively. As will be understood by one skilled in machine shop practice, the shank 11 of the sleeve 10 is trued up by adjustment of the set screw 8g and the set screws 8c, 8c and 8d, 8d. A common way to determine whether the sleeve shank 11 is running true is to place a dial indicator 16 alternately against the two circular sections 11a. The sleeve shank 11 is running true when these dial indicators show a constant reading through at least one rotation of each of the circular sections 11a. When this is done, the extended axis of the sleeve 10 coincides with the axis of rotation of the cradle 8 and the cutting tool of the lathe is adapted to form a cylindrical surface having as its axis the extended axis of the sleeve 10.

The sleeve 10 is detached from the blade and the cutting tool 17, Fig. 12, is placed in contact with the shank 9a of the blade 9, turning out a new permanent shank 9c, the axis of which corresponds to the former axis of the sleeve 10.

The thrust plate A and the leading edge B are thus located in desired position relative to the extended axis of the permanent shank 9c of the blade 9 and the center of gravity of the blade 9 coincides with the axis of said permanent shank 9c.

Thus, for all blades of a particular type manufactured, reference surfaces can be established at uniform distances, within tolerance, from the extended axis of the permanent blade shank. Furthermore, uniform mass characteristics can be obtained by location of the center of gravity of the blade at a predetermined position, for example, on the extended axis of the permanent blade shank.

It will be understood by those skilled in the art that certain types of airplane propellers are manufactured in which the blade center line CL is purposely misaligned with respect to the ex-

tended sleeve axis S, as shown in Fig. 10. The angle formed by the blade center line CL and the extended sleeve axis S is usually about one-half degree, but this has been exaggerated on the drawing for purpose of clarity. With such a blade, the center of gravity cg is usually located on the center line CL. As will be described, this involves a modification of my blade balancing method with respect to the use of the balance stand.

With the blade sleeve unit in seated position within the tubular hub 5 and assuming that the center of gravity cg is located in specified position on the blade center line CL, it is evident that a torque is exerted on the balance assembly, this torque being expressible as the product of the mass of the blade and the perpendicular distance between the center of gravity CG and the extended sleeve axis S.

In accordance with my invention, the weight 5c is placed upon the pin 5b at such distance from the extended sleeve axis S that the torque exerted by this weight 5c is equal in magnitude and opposite in direction relative to the torque established by the offset position of the center of gravity cg with respect to the extended sleeve axis S.

While the invention has been described with respect to certain particular preferred examples which give satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent is:

1. In the art of manufacturing metallic propeller blades having a cylindrical shank portion, the method of aligning the axis of rotation of said shank portion with the center of gravity of said blade, which consists in adjustably securing the blade shank in a hollow fixture having an axis of rotation and spaced circular gaging surfaces concentric therewith, adjusting said fixture relative to said shank to bring said gaging surfaces into concentric relation with the center of gravity of said blade, adjustably supporting said blade and attached fixture in a lathe independently of said fixture, securing said blade in said lathe by adjustment, with said gaging surfaces in concentric relation with the turning axis thereof, removing said fixture from said shank and turning the surface thereof down to a final diameter.

2. In the art of manufacturing propeller blades, the method of machining the shank surface thereof in concentric, co-axial relation with a plurality of airfoil dimension characteristics along said

blade, comprising camber and thrust surface contour, thickness, edge alignment, width and axial center of said blade, which consists in adjustably securing the shank portion of a blade in a hollow fixture having an axis of rotation and spaced, circular gaging surfaces concentric therewith, adjusting said fixture relative to said shank to bring said fixture into concentric alignment with all of said characteristics, placing said blade and attached fixture in a metal turning machine adapted to support said blade independently of said fixture, adjustably securing said blade in said machine to bring said gaging surfaces into concentric relation with the turning axis of said machine, removing said fixture from said shank and turning the surface thereof down to a final diameter concentric with and in axial alignment with all of said characteristics.

3. In the art of manufacturing propeller blades, the method of machining the shank surface thereof in concentric, co-axial relation with a plurality of air foil dimension characteristics along said blade comprising camber and thrust surface contour, thickness, edge alignment, width and axial center of said blade, which consists in adjustably securing the shank portion of a blade in a hollow fixture having an axis of rotation and concentric, spaced, circular gaging surfaces, adjusting said fixture relative to said shank to bring said gaging surfaces in concentric alignment with all of said characteristics, placing said blade and attached fixture in a metal turning machine adapted to support said blade independently of said fixture, adjustably securing said blade in said machine at a point adjacent each end of said blade whereby to bring said gaging surfaces into concentric relation with the turning axis of said machine, removing said fixture from said shank and turning the surface thereof down to a final diameter concentric with and in axial alignment with all of said characteristics.
